US0D1076840S

(12) **United States Design Patent** (10) **Patent No.:** **US D1,076,840 S**
(45) **Date of Patent:** **** May 27, 2025**

(54) **ELECTRONIC MEDIA DEVICE**

(71) Applicant: **Sky CP Limited**, Middlesex (GB)

(72) Inventors: **Edward Snodgrass**, Middlesex (GB);
Chee Wong, Middlesex (GB);
Christopher Weightman, Middlesex (GB)

(73) Assignee: **Sky CP Limited**, Middlesex (GB)

(**) Term: **15 Years**

(21) Appl. No.: **29/832,537**

(22) Filed: **Mar. 28, 2022**

(30) **Foreign Application Priority Data**

Sep. 28, 2021 (GB) 6165985

(57) **CLAIM**

The ornamental design for an electronic media device as shown and described.

DESCRIPTION

FIG. 1 is a front view of an electronic media device showing our new design;

FIG. 2 is a rear plan view thereof;

FIG. 3 is a top plan view thereof;

FIG. 4 is a right side view thereof;

FIG. 5 is a left side view thereof;

FIG. 6 is a front perspective view thereof; and,

FIG. 7 is a rear perspective view thereof.

The broken lines depict portions of the electronic media device that form no part of the claimed design.

1 Claim, 7 Drawing Sheets
